UNITED STATES PATENT OFFICE.

ALLAN ROLAND PYE JOHNSON, OF TORONTO, ONTARIO, CANADA.

DESIGN FOR A SIGNAL FACEPLATE.

Application filed August 12, 1927. Serial No. 23,074. Term of patent 7 years.

To all whom it may concern:

Be it known that I, ALLAN ROLAND PYE JOHNSON, a subject of the King of Great Britain, and a resident of the city of Toronto, in the county of York, in the Province of Ontario, Canada, have invented a new, original, and ornamental Design for a Signal Face Plate, of which the following is a specification, reference being had to the accompanying drawing, forming part thereof.

Fig. 1 represents a front elevation of a signal face plate showing my new design, and Figure 2 is an edge elevation of the same.

I claim:

The ornamental design for a signal face plate, as shown.

ALLAN ROLAND PYE JOHNSON.
